UNITED STATES PATENT OFFICE.

CORYELL BARTHOLOMEW, OF JACKSON, MICHIGAN.

DESIGN FOR A BANDAGE.

SPECIFICATION forming part of Design No. 32,102, dated January 9, 1900.

Application filed November 18, 1899. Serial No. 737,525. Term of patent 14 years.

To all whom it may concern:

Be it known that I, CORYELL BARTHOLOMEW, a citizen of the United States, residing at Jackson, in the county of Jackson and State of Michigan, have invented a certain new, useful, and original Design for a Bandage, of which the following is a specification, reference being had therein to the accompanying drawings, in which—

Figure 1 is a perspective view of a bandage embodying my new design, and Fig. 2 is a longitudinal section thereof.

As shown in the drawings, the leading or material feature of my design consists in the configuration, which comprises a thin substantially cylindrical body with flaring or bell-shaped ends.

A is the body portion of the bandage, which, as shown, is a thin-walled cylindrical tube, and B and C are the flaring or bell-shaped ends, which merge into the tubular portion, as shown. The flaring end C is thickened, as shown in the drawings.

What I claim is—

The design for a bandage, substantially as herein shown and described.

In testimony whereof I affix my signature in presence of two witnesses.

CORYELL BARTHOLOMEW.

Witnesses:

JAMES WHITTEMORE,
H. C. SMITH.
